UNITED STATES PATENT OFFICE.

EDGAR WILSON HEISEY, OF NEWARK, OHIO, ASSIGNOR TO A. H. HEISEY & COMPANY, OF NEWARK, OHIO.

DESIGN FOR A PLATE.

Application filed March 21, 1923. Serial No. 5,551. Term of patent 14 years.

To all whom it may concern:

Be it known that I, EDGAR WILSON HEISEY, a citizen of the United States of America, residing at Newark, in the county of Licking and State of Ohio, have invented a new, original, and ornamental Design for a Plate, of which the following is a specification, reference being had to the accompanying drawings, forming part thereof.

Figure 1 is a view in side elevation of a plate embodying the invention.

Figure 2 is a bottom plan view of a plate showing the physical embodiment of my invention.

I claim,

The ornamental design for a plate, as shown.

EDGAR WILSON HEISEY.
